UNITED STATES PATENT OFFICE

JOSEPH H. KERBER, OF WEST ALLIS, AND EDWARD A. DROTT, OF MILWAUKEE, WISCONSIN, ASSIGNORS TO HI-WAY SERVICE CORPORATION, OF MILWAUKEE, WISCONSIN, A CORPORATION OF WISCONSIN

SNOWPLOW

Application filed June 3, 1931. Serial No. 541,816.

The invention relates to snow plows and more particularly to snow plows adapted to connection to a motor driven vehicle.

Many attempts have been made to provide snow plows that may be attached to motor driven vehicles and more particularly to motor truck chassis but so far as we are aware, these attachments have all been made to set the plow in the front of the machine with the weight of the plow applied to the frame of the vehicle in advance of the front wheels. Where plows are mounted in front as above described the distribution of their weight at the front of the frame has a tendency of cantilevering the frame over the front axle and thus lifting the rear of the truck and consequently lessening the ground contact pressure of the rear traction wheels. Consequently with the front mounted plows, whether the truck is driven entirely from the rear or both from the front and rear axles, the deeper the snow and the harder the plowing, the less traction there is on the rear traction wheels. According to the present invention the plow structure is mounted so as to distribute its weight over the rear traction wheels of the motor truck so that this weight as well as the reaction forces of the snow on the plow during plowing will be exerted downwardly upon the rear traction wheels and thus increase traction and the vehicle is driven backwards during plowing. Thus with the plow structure mounted at the rear of the truck so as to distribute its weight at the rear and over the rear traction wheels, the weight of the plow plus the weight of the snow on the plow and the so-called backward momentum of the vehicle all cooperate so that the weight and traction is increased with the depth of the snow and speed and therefore the deeper the snow, the more traction we have on drive wheels. As an example, we may have up to ten tons of weight directly over the rear axle. Thus the plowing efficiency of the apparatus of our invention is superior to the trucks having front mounted plows and this fact has been definitely established in actual practice. Furthermore by mounting the plow over the

rear traction wheels and going in a backward direction we eliminate side draft when bucking banks after the first trip through the snow since due to mounting of the plow in this manner there is no chance of swinging the truck sideways, whereas with front mounted plows, side draft is one of the big drawbacks and cannot be eliminated. Another advantage of this invention is that due to the plow being set directly ahead of the rear drive wheels we obtain a level traction surface for these drive wheels to obtain full traction on, whereas, with the front mounted plow, the snow rolls back and ahead of the rear drive wheels and causes them to lose traction. Another decided advantage in the present arrangement is that we push our plow directly from the rear axle in the direction of plowing thus giving the frame and springs their full oscillation.

A further object of the invention is to provide a snow plow for connection at the rear of a motor driven truck wherein the plow carrying frame is connected by links to the main frame and to the rear axle and in such a way that the plow may be raised and lowered as desired.

A further object of the invention is to provide a plow construction wherein the center of the plow structure is provided with an outwardly projecting snow cutting blade or divider plate and wherein snow cutting blades are also arranged at the sides of the plow so as to cut through snow banks and thus assist the plow in its work. By using this divider plate on the front of the plow, we can buck snow sideways without having a portion of it roll out in the road on the opposite side of the plow.

A further object of the invention is to provide a simple and novel arrangement of multi-part hoist for raising and lowering the plow.

A further object of the invention is to provide a motor driven snow plow adapted to be operated while the vehicle is travelling backwards in which the framework of the plow structure is so constructed and arranged as not to obscure the vision of the

driver or operator of the plow from his seat on the vehicle.

Other features and advantages will be pointed out in detail in the following specification:

In the drawings, Fig. 1 is a side elevation view of a snow plow embodying the invention.

Fig. 2 is a plan view of the snow plow structure, parts being broken away;

Fig. 3 is a detail sectional view taken on the line 3—3 of Fig. 2;

Fig. 4 is a detail sectional view taken on the line 4—4 of Fig. 3;

Fig. 5 is a front end elevation view of the plow structure at the rear of its propelling truck.

Fig. 6 is a detail sectional view taken on the line 6—6 of Fig. 2;

Fig. 7 is a detail sectional view taken on the line 7—7 of Fig. 2;

Fig. 8 is a detail sectional view taken on the line 8—8 of Fig. 3;

Fig. 9 is a detail sectional view taken on the line 9—9 of Fig. 3;

Fig. 10 is a diagrammatic view of the hoist mechanism.

Fig. 11 is a diagrammatic view of a truck to illustrate the action of the plow embodying the invention.

Referring to the drawings, Figs. 1 and 3, the numeral 11 designates generally a motor driven vehicle of the truck type having the rear traction wheels 12, the usual front steering wheels 13, driver's cab 14, the hood 15 covering the power plant, and the main frame 16 supported in known manner by suitable springs, the rear springs 17 and the rear axle 18 being shown in Fig. 3.

The main frame of the plow includes a sturdy U-shaped arch or bridge member 19, whose sides or legs 20 are suitably braced by diagonal braces 21 connecting them with the transverse beam or top 22, this frame being mounted directly over the rear traction wheels 12, see Figs. 1, 2 and 3. Cutter supporting beams 23 are connected to the legs 20 adjacent the top beam 22 and are also connected and securely trussed to said legs by inclined truss beams 24 which extend from the end extensions 23' of the beams 23 to medial points of the legs 20, it being noted that these parts are formed of heavy sectional channel steel.

Heavy gauge metal plates form the sides of a V-shaped plow blade 25 having cutting edge plates 26 secured thereto at their lower edges. A vertically disposed bulkhead plate 27 is disposed behind the plates 25 and is connected thereto as by rivets 28, see Figs. 2, 3 and 9. A bottom plate 29 is secured in front as by welding to the blade portions 25 and is similarly secured to the bottom portion of the bulkhead 27 and has rearwardly extending portions 30 carrying shoes or run-

ners 31 and also connected to the bases of the legs 20 adjacent the rear wheels. The blade portions 25 are also securely tied to the legs 20 of the frame member 19 by side plates 32 secured as by rivets 33 to said legs, see Figs. 3, 8, and 9. Thus the weight of the whole plow structure is distributed through the connection of the parts above described with the bridge member 19 over the rear end of the frame and over the rear traction wheels.

A V-shaped plate frame construction comprising the top plate 34 is securely riveted to the upper edges 35 of the blade portions 25 and to the plates 32, see Figs. 3, 6 and 7, and the structure thus far described is further braced by diagonal braces or truss members 36 securing the outer ends of the divergent beams 23 to angle brackets 37 at the apex of this V-shaped frame, see Fig. 5.

The outer ends of the beams 23 have depending spaced side plates 38 bolted or otherwise suitably secured thereto and the inner one of each of these plates is connected by a cross brace member 39 with the adjacent diagonal inclined brace 36, see Fig. 5.

Side bank cutting knives 40 are pendently supported from the outer ends of the beams 23 by an upper bolt 41 connecting the upper ends of said knives with said beams and the plates 38 between which these knives extend and by a lower shearable bolt 42 passing through said knives and plates 38 but adapted to be sheared off in case the knife encounters too much resistance so that said knife or knives then pivoting on their upper bolts 41 may swing freely toward the truck body. These knives have sharp cutting edges 43 extending the length thereof and work in paths in advance of and slightly beyond the ends of the main plow blade portions 25 as shown in Figs. 2 and 5.

A centrally disposed cutting blade or divider plate 44 is mounted to project in front of the apex of the blade portions 25 and is secured thereto by angled brackets 45 riveted thereto and to said portion, and acts to cut down the resistance of the material against the plow and prevents the snow from one side of the plow working over to the other side and thus keeps the load divided.

Side snow deflecting wings are also associated with the top portions of the blade portions 25 and are arranged for pivoting at various inclinations with respect thereto as shown more in detail in Figs. 6 and 7 wherein it is noted that each metal strap 47, shown in Figs. 2 and 3 as riveted to the backs of the wings, has a hinge extension 48 working in a hinge slot 49 in the plates 34 and that said wings have spaced sets of pivot ears 50 carrying bolts 51 connected by adjustable links 52 with pivot pins 53 mounted in similar spaced sets of ears 54 on the plates 34, said links having a plurality of spaced

holes for adjustably receiving said pins 53 to and is wound upon a hoisting drum 92 vary the effective length of the links and mounted on the truck body and adapted to be thus vary the inclination of the wings 46 relative to the face of the plow blades to suit 70 different operating conditions.

For connecting the plow structure with the truck, an upper set of spaced links 56 and a lower set of spaced links 57 are provided, see Fig. 3. Each upper link 56 is pivotally connected by a pin 58 to pivot ears 59 secured to the bulkhead plate 27 and by pivot bolt 60 to a frame member 61 secured to the side bar 62 of the main frame 16 of the truck over the rear traction wheels 12. Each link 15 57 is pivotally connected by a pin 63 to pivot ears 64 on the blade portion 25 and by a pivot bolt 65 to a bracket 66 secured to the spring bolster 67 of the rear axle by the hanger bolts 68. These links 57 transmit thrusts during 20 plowing to the rear axle and at a point below the same to assist in getting traction and also to allow free action of the springs 17.

The frame members 61 each have an upright frame member 69 secured thereto and 25 braced by an angular plate 70 and guide plates 71 secured to angles 72 to the backs of each link 56 intermediate its ends slide on the uprights 69 and maintain said links in proper lateral alignment.

30 The lower links 57 work through elongated slots 73 in the bulkhead plate 27 and are maintained in proper lateral alignment by angled guides 74 secured to said plate 27, see Figs. 3 and 4.

35 A triangular shaped frame or lever 75 is formed by the spaced channel bars 76 whose converging ends are secured in spaced relation by a tie plate 77 and whose diverging ends carry channel shaped brackets 78 provided with pins 79 carrying rollers 80 adapted to engage the laterally extending side 81 of an angled plate 82 secured to the bulkhead plate 27, see Figs. 2 and 3. The bars 76 intermediate their ends have pivot brackets 83 secured thereto through which a pivot shaft 84

40 mounted in the upright frame members 69 and plates 70 passes. These uprights 69 and plates 70 are braced at their upper ends by a transverse tie bar 85 connecting them together. The pivot point for the lever 75 being at the rear of the truck frame on the frame parts including the frame members 61, the weight of the plow structure and its load 45 is applied over the rear traction wheels 12.

50 The spaced converging ends of the bars 76 carry a shaft 86 upon which a series of pulleys 87 are mounted, said pulleys cooperating with a similar set of pulleys 88 mounted on a shaft 89 carried by the frame members 61 on the truck to form operating connections for a multi-part hoist line or cable 90 which is trained over said pulleys as shown in Fig. 10 and is dead ended at one end as at 91 to the frame of the truck and after 55 passing over the pulleys proceeds forward

and is wound upon a hoisting drum 92 mounted on the truck body and adapted to be operated in any suitable manner from the power system of the truck and under the control of the operator in the cab 14. Thus 70 winding up the cable 90 on the hoist drum will act to swing the inner end of the frame 75 toward the truck and thus raise the other end which in turn through the rollers 80 acts on the plate 82 to raise the entire plow structure. Thus the plow may be set so that the 75 shoes 31 rest on the ground over which the plow is running or it may be raised above the same.

In working the plow, the vehicle proceeds 80 in a backward direction when considering the front of the truck and it will be noted from Figs. 1 and 5 that the plow operator has a clear vision from his seat in the cab through the space 93 between the parts 22 85 and 36 of the plow frame to the road in front of the plow.

In order to explain more clearly the action of the plow structure when combined with a motor truck as described above, we have 90 prepared the illustrative diagram shown in Fig. 11 of the drawings wherein the numeral 94 designates the chassis or frame of the truck, 13 the front wheels, 12 the rear traction wheels, 95 and 96 arrows indicative of applications of force as applied to the vehicle. Where, as is usual, the plow structure is applied to the front of the vehicle in front of the front wheels the weight of the plow and the reactive forces acting in the direction of 95 the arrow 95 will have a tendency to swing or cant the truck frame about the front wheels and thus tend to lift the rear wheels 12 from their traction surface and lessen the ground contact pressure of these rear 100 wheels and consequently the deeper the snow and the harder the plowing the less traction there is on the rear wheels. Whereas in the present construction the weight of the plow plus the weight of the snow on the plow and 105 the reactive forces occasioned by the movement of the plow into the snow acts in the general direction indicated by the arrow 96 over the rear traction wheels, the weight and the forces acting to hold the plow to its work 110 increases with the depth of the snow and speed and consequently the deeper the snow the greater will be the forces exerted in the line of the arrow 96 and hence the greater the traction on the rear wheels 12. Also by 115 mounting the plow over the rear traction wheels and driving the truck in a rearward direction, there is no chance of swinging the truck sideways when bucking banks after the first trip through the snow and thus side 120 draft is prevented. Furthermore, as the plow blades are mounted to work directly in front of the rear wheels, the chance for snow rolling back under these rear wheels and interfering with the level traction surface pro- 125 130

duced by the plow is prevented. Furthermore since the plow is mounted so that it is pushed directly through the links 57 from the rear or drive axle in the direction of plowing the full action of the springs 17 between said axle and the truck frame is not interfered with.

It will also be noted that as the plow proceeds through the snow, the sides of the bank 10 will be cut through by the knives 40 and the center of the material being plowed will be cut through by the blade 44 and that the V-shaped plow blade will throw the snow to the sides of the road assisted in deep snow 15 by the adjustable side wings 46. It is also to be noted that the entire plow structure and its frame are all one unit, that the bulkhead plate 27 is disposed directly behind the rear end of the main frame of the truck and 20 that the legs 20 of the frame member 19 straddle the rear wheels 12 of the truck.

We desire it to be understood that this invention is not to be limited to any particular form or arrangement of parts except in so 25 far as such limitations are included in the claims.

What we claim as our invention is:

1. The combination with a motor driven vehicle of the truck type having front steering wheels and rear traction wheels, and a main frame above said wheels, of a snow plow including a fixed blade connected to the rear portion of the main frame with its weight distributed directly over said rear traction 30 wheels and operating at the rear of said truck while the truck is driven in a rearward direction, and means for bodily moving said plow vertically.

2. The combination with a motor driven vehicle of the truck type having front steering wheels, rear traction wheels, a main frame, wheel supporting axles and springs connecting said axles with the main frame, of a snow plow operating at the rear of the 40 truck while said truck is driven in a rearward direction, pivoted means for connecting said plow to the main frame, pivoted means for connecting said plow to the rear wheel supporting axle, said plow being mounted on the rear of said main frame to distribute its weight over said rear traction wheels, and means for bodily moving said plow vertically.

3. The combination with a motor driven vehicle of the truck type, having front steering wheels, rear traction wheels, a main frame, wheel supporting axles and springs connecting said axles with the main frame, of a snow plow operating at the rear of the 50 truck while said truck is driven in a rearward direction and including a frame, pivoted means for connecting said plow to the main frame, pivoted means for connecting said plow to the rear wheel supporting axle, and hoisting mechanism on the main

frame over said rear traction wheels and engageable with the plow frame for raising and lowering said plow.

4. The combination with a motor driven vehicle of the truck type including a main frame, rear traction wheels, rear axle and spring suspension for said frame from said axle, of a snow plow having a V-blade and a frame including a bulkhead extending between the sides of said V-blade, links connecting said bulkhead with the sides of the main frame of the truck at the rear thereof, and links connecting the sides of said V-blade with said rear axle.

5. The combination with a motor driven vehicle of the truck type including a main frame and rear traction elements, of a plow structure connected to the rear portion of said frame and operating at the rear of said frame, a hoisting lever for said plow structure pivotally mounted in said main frame above said traction elements to distribute the weight of said plow structure over said traction elements and operatively connected to said plow structure for raising the same, a hoisting drum on said vehicle, and a hoisting cable mounted on said drum and having a multi-part hoist connection between said lever and frame.

6. The combination with a motor driven vehicle of the truck type including a main frame and rear traction elements, of a plow structure connected to the rear portion of said frame and operating at the rear thereof, a hoisting lever comprising a triangular shaped frame pivotally mounted intermediate its ends on said main frame above said traction elements and operatively connected at one of its spaced points to said plow structure and carrying a series of pulleys at its other end, a series of pulleys mounted on said main truck frame, a hoist drum and a hoisting line wound on said drum and extending between said series of pulleys for moving said hoisting lever.

7. The combination with a motor driven vehicle of the truck type having a chassis frame and rear wheels, a plow having a V-shaped blade working at the rear of said chassis frame and having a frame having a bridge member provided with legs that straddle said rear wheels, and means for connecting said plow structure to said vehicle for vertical movement of said structure relative to said vehicle.

8. In a snow plow for motor driven vehicles, the combination with a plow blade, of a frame connected with said blade and having arms disposed above said blade and extending laterally thereof, and bank cutting blades pendants supported from said arms in advance of said plow blade.

9. In a snow plow for motor driven vehicles, the combination with a V-blade plow, of

5 a cutting blade projecting forwardly from the apex of the plow, a frame connected with said plow, side bank cutting blades carried by said frame, adjustable side wings for said plow, and means for connecting said plow at the rear of a motor driven vehicle.

10. A plow structure comprising a V-blade plow, a bulkhead between the sides of said blade, a U-shaped frame connected to said bulkhead, arms connected with the upper portion of said frame and extending laterally of the plow, braces between the outer ends of said arms and bulkhead, and cutting blades depending from the outer end portions of said arms.

11. The combination with a motor driven vehicle of the truck type having an operator's station on the front portion of said vehicle, of a plow structure including a plow and a frame including a U-shaped arched member having legs straddling the rear portion of the vehicle, brace means between said frame and the plow inclining downwardly from the side of said frame to the central portion of the plow and thus affording a clear line of vision from the operator's station through the open space above said brace means.

12. The combination of a motor driven vehicle of the truck type having a main frame and rear traction wheels, of a snow plow structure having a fixed blade, means for mounting said plow structure for operation at the rear of said vehicle to distribute the weight of said structure, its load and the reactive forces due to plowing directly over said traction wheels to increase the tractive effort of said wheels as the depth of the snow increases including hoisting mechanism for bodily raising and lowering said plow structure.

13. The combination with a motor driven vehicle of the truck type having a main frame, traction elements at the rear of said frame and a rear axle, of a plow structure mounted for operation at the rear of said vehicle, hoisting means engageable with the plow structure for adjusting its working position above the ground and supporting said structure from the vehicle to distribute its weight and load directly over said traction elements, and a pushing connection between

said plow structure and said rear axle operable in any position of vertical adjustment of said plow structure.

14. The combination with a motor driven vehicle of the truck type including a main frame, rear traction wheels, rear axle and spring suspension for said frame from said axle, of a snow plow including a frame mounted at the rear of said frame, links connecting said plow frame with said main frame of the truck, and links connecting said plow with rear axle.

15. The combination with a motor driven vehicle of the truck type including a main frame, rear traction wheels, rear axle and springs connected to said rear axle and operatively connected to said frame, of a snow plow structure mounted at the rear of said frame, links connecting said plow structure with said main frame, and links connecting said plow structure with the rear axle below said springs.

16. The combination with a motor driven vehicle of the truck type including a main frame, rear traction wheels and rear axle, of a snow plow including a frame arranged to straddle said wheels, means for supporting said frame on the rear of said main frame over said traction wheels, and a pushing connection between said plow and said rear axle.

17. The combination with a motor driven vehicle of the truck type having a main frame, traction elements at the rear of said frame, a support for said traction elements, and a spring suspension from said frame for said support, of a plow structure mounted for operation at the rear of said vehicle as said vehicle is driven in a rearward direction and vertically adjustably supported from the vehicle to distribute its weight and load over said traction elements, and a pushing connection between said plow structure and the support for said traction elements operable in any position of vertical adjustment of said plow structure.

In testimony whereof, we affix our signatures.

JOSEPH H. KERBER.
